PILL BOX UNIT

Emil H. Orenick, Parma, Ohio, assignor to The State Tool & Die Company, Cleveland, Ohio, a corporation of Ohio

Application July 28, 1954, Serial No. 31,637

Term of patent 14 years

(Cl. D52—2)

FIG. 1

FIG. 3

FIG. 2

FIG. 4

FIG. 5

FIG. 6

Figure 1 is a perspective view of a pill box unit, embodying my new design;

Figure 2 is a right end view thereof;

Figure 3 is a top plan view thereof;

Figure 4 is a bottom plan view of the same;

Figure 5 is a rear elevational view of the pill box unit; and

Figure 6 is a top plan view of the same, showing the cover in its open position.

I claim:

The ornamental design for a pill box unit, substantially as shown.
